UNITED STATES PATENT OFFICE.

JOHN R. VAN WORMER, OF TOLEDO, OHIO.

PAPER-BOX-BLANK MACHINE.

939,571.

Specification of Letters Patent. Patented Nov. 9, 1909.

Application filed January 23, 1909. Serial No. 473,849.

To all whom it may concern:

Be it known that I, JOHN R. VAN WORMER, a citizen of the United States, residing at Toledo, in the county of Lucas and State of Ohio, have invented certain new and useful Improvements in Paper-Box-Blank Machines, and do declare the following to be a full, clear, and exact description of the invention, such as will enable others skilled in the art to which it appertains to make and use the same, reference being had to the accompanying drawings, and to the figures of reference marked thereon, which form a part of this specification.

In the manufacture of blanks for paper or pasteboard boxes, it is desirable to form such blanks from rolls of paper or pasteboard instead of from separate sheets. A serious difficulty encountered in the forming of such blanks from continuous rolls is that the rolls are extremely heavy, and, as a consequence, when the rolls are set to revolving, the momentum is so great that the heavy paper or pasteboard is caused to buckle and break during the pause of the material while the cutting and creasing of the blank takes place. This difficulty has been so great as to prevent the satisfactory use of heavy paper or pasteboard when it is fed directly from rolls to the blank-cutting machinery.

My invention relates to and its object is to provide a machine for overcoming the difficulties here indicated, and, more particularly, to furnish devices by means of which the material for box-blanks may be fed directly from a roll to the blank-cutting mechanism of my machine, and in which the feed-rolls and the paper-roll shall be caused to pause during the action of cutting and creasing dies, thus keeping the stock straight and unbroken and preventing waste of material.

A further object of my invention is to provide means for automatically stopping the machine in case the web of paper should become buckled or formed into folds, as it is fed between the platen and the die of the machine.

I attain these objects by means of the devices mechanism and arrangement of parts hereinafter shown and described, and illustrated in the accompanying drawings, in which,—

Figure 1 is a side elevation of the front

end of my machine; Fig. 2 a top-plan view 55 of the brake-mechanism for the paper roll, hereinafter referred to; Fig. 3 a front end view of one side of my machine with the paper roll supporting frame or bracket removed, and Fig. 4 a side elevation of the 60 same, taken on line α — α Fig. 3.

Like parts are represented by corresponding numerals throughout the drawings.

In the drawings, 1 is a stout frame, supporting a table bed or platen 2, and forming 65 a housing in which the carrier 3 for the cutting and creasing die 3^a reciprocates vertically. The frame or housing 1 also forms bearings for the drive-shaft 4 and for the train of gears 5, 6, 7, 8 and 9. The shaft 70 8^a, upon which the gear 8 is secured, extends through the frame of the machine and carries at each end a crank. At opposite sides of the machine are pitmen 10 connected at their lower ends to crank-pins 11 carried by 75 the shaft 8^a, and at their upper ends connected to wrist-pins 12 upon the reciprocating die carrier 3.

Rigidly secured upon the gear 9—and radially thereof—is a box or housing 13 in 80 which is journaled a screw 14, operatively engaged with the radially movable crankpin 15. Pivottally connected with the crankpin 15 is a connecting rod or bar 16 pivottally connected, as at 17, with rack-bar 18. 85 The rack-bar reciprocates in suitable guides and its teeth engage the teeth of a pinion 19 on shaft 20 journaled in the frame of the machine and which carries a feed-roll 21. Directly above the feed-roll 21 is a pressure-roll 22 journaled in the frame of the machine. Between these two rolls the web or strip of paper 23, to be operated upon, is fed. The pinion 19 engages shaft 20 by means of a pawl-and-ratchet, (not shown 90 in the drawings), or other equivalent devices, by means of which the feed-roll 21 is caused to revolve only with the downward movement of the rack-bar 18.

For the feed-roll 21, I provide a brake-shoe 24 mounted upon or rigidly connected with one end of a lever 25, fulcrumed, as at 26, upon the frame of the machine, the other end of the lever being inclined, as at 27, into the path of a pin 28 secured to and projecting outwardly from the rack-bar 18. As the rack-bar nears the end of its downward movement, the pin 28 engages the lever,

causing the lever to swing slightly and to throw the brake-shoe into close engagement with the feed-roll 21, thus causing the feed-roll to remain stationary until the brake is released by the upward movement of the rack-bar.

Projecting forwardly from the front end of the machine is a stout bracket or frame 29 in which is journaled a shaft 30 upon which is rigidly mounted and secured the paper-roll 31 from which the web or strip of paper or pasteboard is fed to the dies or cutting mechanism. The upper forward end of the frame 29 is inclined and notched, as at 32 to form bearings for the ends of the shaft of the guide-roll 33. Rigidly secured to one end of the shaft 30 is a friction disk 34. 35 is a two-part friction-clutch which embraces the friction-wheel 34. The two parts of the friction-clutch are pivoted at one side upon the bracket or frame 29, as at 36. At their other side the two parts of the clutch 35 are provided with opposed lugs or ears 37. These lugs or ears are tapped for the reception of a screw 38, the thread of the screw being of "quick" lead. The screw 38 is provided with an arm or handle 39 through which passes loosely a rod 40. Upon the rod 40, at opposite sides of the arm 39, are adjustable stops 41, which alternately engage the arm 39 as the rod 40 is caused to move to and fro. The other or forward end of the rod 40 is pivotally connected with the adjustable crank-pin 15, as at 42.

The operation of my machine, thus far described, is as follows:—The parts being assembled, as illustrated and explained; the die-carrier being provided with the proper cutting and creasing dies 3^a; a paper roll being mounted upon its shaft 30, as above described; the paper-web 23 being threaded over the roll 33 and between the rolls 21—22 and between the die and platen; the crank-pin 15 being radially adjusted upon the gear 9 to give exactly the required movement to the crank-bar 18 and the feed-roll 21 and to insure the feed of the proper amount of paper to the cutting mechanism, motion is communicated to the shaft 4 and thence to the other moving parts, as will be now understood. As the rack-bar moves downwardly, the feed-roll 21 is caused to revolve quickly, pulling from the paper roll 31 the requisite amount of paper and feeding it beneath the die. As the feed-roll and paper roll revolve quite rapidly, they acquire considerable momentum, and, unless stopped at the instant the proper amount of paper is fed to the die, a large amount of surplus paper would be fed from the paper roll, and the paper beneath the die would not lie smooth and flat. This difficulty is avoided, as will be seen, by the pin 28 moving along the arm 27 of the brake 24, which sets the brake against the feed-roll. At the same

time the movement of the rod 40 gives a part turn to the screw 38, which causes the clamping members of the clutch 35 to tightly clamp the friction disk 34 on the shaft of the paper roll, thus also bringing this roll to a gradual but quick stop in its rotation. 70

It will be seen that when large blanks are to be cut, or when several smaller blanks are to be cut simultaneously, it may be necessary to feed to the cutting mechanism a considerable amount of paper or stock at each throw of the cutting die. This may be gaged and controlled exactly by the adjustment of the crank-pin 15 on the gear 9, for, as will be obvious, if the crank-pin is set exactly at the center of the gear 9 there will be no movement at all of the rack-bar 18 or the feed-roll 21, but if the crank-pin be moved to its outer limit, the forward rotation of the feed-roll will be rapid and sufficient to feed a considerable amount of paper to the cutting mechanism at each throw of the rack-bar. It will also be seen that the more rapid the feed of the paper between the successive cuts of the dies, the greater will be the momentum of the feed-roll and the paper roll to be overcome, so that it will be necessary to set the brakes upon the feed-roll and the paper roll with considerably more force than if these rolls were moved but a short distance between cuts. The increased throw of the rods 16 and 40 provide automatically for the required increase of brake resistance, for it will be seen that the greater the throw of these two rods, the more tightly will the brakes be set at each rotation of the wheel 9. The two brakes 24 and 35, it will be understood, have sufficient resiliency to permit the variation of strain here indicated. 90

While my machine is designed to automatically perform its work and to use up the roll of material with which it may be supplied, it sometimes happens that, owing to flaws or breaks or tears or weak spots in the paper, it is not fed forward from the feed-rolls to the proper point beneath the die. When this happens, the paper begins to buckle and double and forms irregular folds, which might, unless attended to, impose undue strains upon the machine with disastrous results. This contingency is obviated by the mechanism now to be described. 105

In Figs. 3 and 4 are shown a starting and stopping handle 43, which throws a belt to and from fast and loose pulleys or controls equivalent stopping and starting devices. This handle is held normally in stopped position by spring 44. 45 is a stop-bar or latch, beveled on its lower end, moving vertically in housing 46 and held normally depressed by spring 47. The lower beveled end of the bar 45 is in the horizontal path of the lever 43. When this lever is swung 110

into starting position, it strikes the beveled lower end of the stop 45, lifting the stop which immediately falls behind the lever when it has reached the starting position, 5 and so holds the starting lever until the stop is again lifted. The upper end of the stop-bar 45 has, as at 48, a hook which engages one arm of a bell-crank lever 49, fulcrumed, as at 50, upon a rod 51 which extends to 10 within convenient reach of the operator, and which is, at its outer extremity, formed as a crank, as at 52. The other arm of the bell-crank lever 49 is connected by a wire 53 with one arm of a bell-crank lever 54 15 rigidly secured upon a rod or shaft 55 journaled in the frame of the machine directly beneath the bed-plate or platen 2 near its forward margin. The other arm 56 of the lever projects beyond the forward margin 20 of the bed-plate 2 close to the point where the feed-rolls deliver the paper onto the bed-plate or platen, as illustrated in Fig. 4. The rod or shaft 55 extends entirely across the machine and is supplied at intervals 25 with a number of the arms or fingers 56.

Should the paper, as it leaves the feed-rolls, fail to feed forward upon the bed-plate, and, as a result, begin to crumple up at the rear side of the feed-rolls, the paper 30 will be forced down upon the projecting fingers 56, (see Fig. 4), pressing these fingers downwardly, causing the rod 55 to tilt, swinging the arm 54 upwardly, pulling on the wire 53, swinging the bell-crank lever 35 49, and thus pulling the stop-bar 45 out of engagement with the starting lever 43. Now the spring 44 instantly pulls the lever into stopped position and the machine is 40 stopped without injury to any of the parts. Since the rod 51 terminates in the crank 52, it will be seen that the machine may be 45 manually stopped by giving the crank a part turn, thus pulling the stop-bar out of engagement with the starting lever, as above described.

Having described my invention, what I claim and desire to secure by Letters Patent is—

1. In a machine of the described character, a co-acting platen and reciprocating die-carrier, means for revolubly supporting a paper roll, a feed-roll adapted to feed the paper from such paper roll between the platen and the die-carrier, means for actuating the feed-roll between the working strokes of the die-carrier, a brake-mechanism for the feed-roll, a brake-mechanism for the paper roll support, and means for actuating said two brake-mechanisms in harmony with the movement of the die-carrier.

2. In a machine of the described character, a co-acting platen and reciprocating die-carrier, means for revolubly supporting a paper roll, a feed-roll adapted to feed the 65 paper from such paper roll between the

platen and the die-carrier, means for actuating the feed-roll between the working strokes of the die-carrier, a brake-mechanism for the feed-roll, a brake-mechanism for the paper roll support, means for actuating 70 said two brake-mechanisms in harmony with the movement of the die-carrier, and means for varying the rotations of the feed-roll independently of the movement of the die-carrier.

3. In a machine of the described character, a co-acting platen and reciprocating die-carrier, means for revolubly supporting a paper roll, a feed-roll adapted to feed the paper from such paper roll between the 80 platen and the die-carrier, means for actuating the feed-roll between the working strokes of the die-carrier, a brake-mechanism for the feed-roll, a brake-mechanism for the paper roll support, means for actuating 85 said two brake-mechanisms in harmony with the movement of the die-carrier, and means for varying the rotations of the feed-roll independently of the movement of the die-carrier, and for correspondingly varying the 90 stress of the brake-mechanisms.

4. In a machine of the described character, a blank-cutting mechanism, means for revolubly supporting a paper roll, a feed-roll adapted to feed the paper from such 95 paper roll to said cutting mechanism, a radially adjustable crank, driving connections between the crank and the feed-roll, a brake for the paper roll support and connections between the crank and said brake.

5. In a machine of the described character, a blank-cutting mechanism, means for revolubly supporting a paper roll, a feed-roll adapted to feed the paper from such paper roll to said cutting mechanism, a radially adjustable crank, driving connections between the crank and the feed-roll, a brake for the paper roll support, a brake for the feed-roll and connections between the crank and said brakes.

6. In a machine of the described character, a blank-cutting mechanism, a feed-roll adapted to feed paper to such mechanism, a stopping mechanism for the machine, a detent for holding the stopping mechanism in 115 inoperative position, a series of fingers pivotally supported parallel with and near to the path of such paper, and connections between the fingers and the detent.

7. A machine for forming box-blanks, 120 comprising a coöperating platen and die-carrier, a train of gears operatively connected with the die-carrier, means for revolubly supporting a paper roll in operative relation to the die-carrier and platen, a feed-roll adapted to feed paper from such paper roll to the die-carrier and platen, a radially adjustable crank upon one of the gears of 125 said train, a pinion upon the shaft of the feed-roll, a rack connected with said crank 130

and with said pinion, a brake for the feed-roll, a brake for the paper roll carrier, and connections whereby the brakes are actuated in harmony with the movement of the crank, combined with a series of fingers pivotally disposed near to the discharge side of the feed-roll, a stopping mechanism for the machine, and connections between said fingers

and said stopping mechanism, substantially as described. 10

In testimony whereof I affix my signature in presence of two witnesses.

JOHN R. VAN WORMER.
